United States Patent Office

Des. 185,726
Patented July 21, 1959

185,726

PLASTIC SHEET MATERIAL

Russel Wright, New York, N.Y.

Application February 17, 1959, Serial No. 54,640

Term of patent 14 years

(Cl. D87—3)

The single figure of the drawing is a plan view showing within the broken lines one complete repeating unit of my new design.

I claim:

The ornamental design for a plastic sheet material, substantially as shown.
